CLAIM

The ornamental design for a signal warning and displaying lamp, as shown and described.

DESCRIPTION

FIG. 1 is a front elevational view of a signal warning and displaying lamp showing my new design;

FIG. 2 is a rear elevational view thereof;

FIG. 3 is a top plan view thereof;

FIG. 4 is a bottom plan view thereof; and,

FIG. 5 is a left side elevational view thereof, the right side elevational view being a mirror image of the left side elevational view.

In the drawings, the broken line showing of the globe for a lamp depicts environmental subject matter and forms no part of the claim.
